CLAIM

The ornamental design for a x-ray imaging system, as shown and described.

DESCRIPTION

FIG. 1 is a front, top and right side perspective view of a x-ray imaging system showing our new design;

FIG. 2 is a front elevational view thereof;

FIG. 3 is a rear side elevational view thereof;

FIG. 4 is a top plan elevational view thereof;

FIG. 5 is a bottom plan view thereof;

FIG. 6 is a right side view thereof; and,

FIG. 7 is a left side elevational view thereof.

In FIG. 1, the bed portion is shown in a lower position relative to the base portion than in FIGS. 2, 3, 6, and 7.

The broken lines in the drawing figures are included for the purpose of illustrating portions of the x-ray imaging device that form no part of the claimed design.
